SHEET FEEDING DEVICE

Karl Theodor Lang, Radebeul, Germany

Application April 21, 1939, Serial No. 269,082
In Germany December 10, 1938

10 Claims. (Cl. 271—53)

This invention relates to a device for insuring accurate feeding of the sheets of a sheet printing machine with respect to the gauges of the feed table.

5 In some of the known devices of this class the sheets caught by the grippers of a rotary sheet feeder are moved away from the pivot of the rotating feeder by special guides and are withdrawn from the feed table at a speed greater than the circumferential speed of the sheet feeder. The sheet guides comprise for instance toggle levers which cooperate in the rotary motion of the sheet feeder and are controlled by a stationary cam disc.

10 15 It has further been proposed to employ blast air for the same purpose.

The known means are, however, open to the objection that they do not permit high operating speeds, since the sheet guides represent means 20 that have to be separately controlled and curves involve a restriction to certain speeds only.

Compared with the known art, the invention overcomes the drawbacks mentioned by employing as sheet guide a sheet carrying drum or the 25 surface line of the cylinder, which drum rotates about a pivot eccentrically disposed relative to the center of the path of the grippers. The sheet carrying drum and the grippers are connected by suitable means, as a crank guide, to provide 30 for equal rotary motion. In this way, only rotary elements are provided, and it is evident that two concentrically rotating members admit of any desired operating speed.

35 It is advantageous to render adjustable the eccentricity between the center of the path of the grippers and that of the sheet carrying drum.

The sheet carrying drum is preferably eccentrically arranged on the shaft of the supports for the grippers, and this shaft is connected with the 40 drum by a coupling permitting radial motion and insuring rotary motion.

In further accordance with the invention an additional increase in speed can be attained by 45 providing besides the sheet guide or press-out member connecting with the preliminary grippers another such member preferably constructed like the first one, both guides or members being guided parallel yet oppositely in their eccentricity. By 50 varying the relative eccentricity the speed at which sheets are withdrawn can be regulated.

The invention is illustrated by way of example in the accompanying drawings, in which—

Figures 1, 2 and 3 are side views of the device 55 at different operating positions;

Fig. 4 is a longitudinal section of the shaft of the gripper carriers, and

Figs. 5 to 7 are side views of a modification, operating with several sheet guides or press-out members, at different working positions.

5

More particularly:

Figure 1 shows the device at the moment when the sheet is passing from the feed table to the preliminary grippers;

Fig. 2 shows the device when a sheet is transferred to the feeding means according to the invention;

Fig. 3 shows the position after the sheet has been transmitted to the impression cylinder.

The sheets 1 are placed in known manner on 15 the feed table 2 and passed by the preliminary grippers 3 to the feeding device according to the invention. 4 designates the impression cylinder provided with the grippers 5.

The device according to the invention substantially comprises two parts. One of these parts is represented by the grippers 6 for the sheets. The grippers 6 are arranged on the carriers 7 and rotate about a shaft 8 in a circular path 9. The shaft 8 is rotatably disposed in the machine 25 frame 10. If only the grippers 6 were provided the sheets would be moved over their entire length in a circular path.

The second part of the device according to the invention is, however, a sheet carrying drum 11 30 eccentrically positioned on the shaft 8 of the gripper carriers 7 and having for instance the shape shown. The center of rotation of the drum 11 is located at 12, and the eccentricity between the shafts 8 and 12 is designated x.

To enable the drum 11 to cooperate in the rotary motions of the grippers 6 both the grippers 6 and the drum 11 are connected by suitable means, as a crank guide 13, 14, the pin 13 being positioned on the carrier 7 and the drum 11 having a 40 slot guide 14 in which the pin 13 can be radially displaced during rotation.

The eccentricity x between the center 8 of the path of the grippers and the center 12 of the drum 11 is preferably adjustable.

35

45 The device operates as follows:

When the shaft 8 is driven it drives also the grippers 6 in the direction of rotation shown in Figs. 1 to 3. In the position shown in Fig. 2 the sheets pass from the preliminary grippers 3 to 50 the grippers 6 and the front end of the sheets moves through the circular path 9. At the point of contact with the printing cylinder 4 the sheet 1 is transferred from the grippers 6 to the grippers 5 of the cylinder 4, but the rear end of the 55

sheet 1 is pressed out radially by the sheet carrying drum 11, so that the acceleration of the rear end of the sheet will be equal to double the eccentricity or $2x$. This involves the advantage that the sheets can be fed again more rapidly to the table 2. Tests have shown that the device operates at a very high speed.

In the modified device shown in Figs. 5 to 7 the gripper 6 arranged below the preliminary gripper 10 moves in the direction of the arrow shown in the circular path A, B indicating the path of the preliminary gripper. Eccentrically to the shaft 8 the press-out member or sheet guide is arranged which is rotatable about the pivot 12 and substantially 15 comprises a cylindrical surface 11 formed so that at its running-on end it is tangent to the circular path B when the sheet is being transferred. The press-out member 11 possesses a link-guide 28 in which a roll 29 rotatably disposed on the gripper 6 moves. When the gripper 6 rotates in the direction of the arrow the press-out member 11 is moved also by means of the roll 29 and the link 28.

Below the press-out member 11 an additional 25 conveying gripper 31 is positioned on a shaft 30 for guiding the sheet on the circular path C, the gripper 31 rotating in a direction opposite to that of the gripper 6. Parallel thereto, but oppositely eccentrically, a second press-out member is 30 formed at 32 on the superficies 33 of a cylinder. The circular paths A, B, C are tangent to each other. The press-out member or sheet guide 33 is driven again by a link-guide 34 and a roll 35 disposed on the gripper 31. The circular path C 35 is tangent also to the path of motion, not shown, of the grippers of the printing cylinder 4 which rotates in a direction opposite to that of the gripper 31. Brushes 37, 38 and 39, which may be replaced of course by blasts, etc., smooth the sheet 1 during operation.

The device shown in Figs. 5 to 7 functions as follows:

In the position shown in Fig. 5 the preliminary gripper 3 receives the sheet 1 from the table 2, 45 the gripper 6 being in a position immediately preceding taking over. In the position shown in Fig. 6 the sheet 1 is taken by the gripper 6 from the preliminary gripper 3 and withdrawn further, the press-out member or sheet guide 11 50 operating in the rotary motion. Owing to its eccentric position and its form, the member 11 extends during its rotation with a portion of the circumference of the cylindrical surface beyond the range of the circular path A, whereby quicker 55 withdrawal of the sheet 1 from the table 2 is effected. After a rotation of approximately 180° from the point of transition the sheet 1 is delivered by the gripper 6 to the gripper 31 rotating in opposite direction. During the rotation of the 60 gripper 31 the press-out member or sheet guide 33 acts in a similar manner as the member 11 by extending with its cylindrical surface beyond the circumference of the circular path C thereby 65 effecting accelerated withdrawal of the sheet 1 from the member 11, as clearly shown in Fig. 7. The sheet 1 is thus accelerated twice and therefore removed from the table 2 with extraordinary rapidity. The sheet 1 is finally delivered by the grippers 31 to the grippers of the impression cylinder 4 in a manner not shown.

Any number of press-out members or sheet guides may be interposed one after the other, their number and dimensions depending on the length of the sheet to be withdrawn.

I claim:

1. A device for insuring accurate feeding of the sheets of a sheet printing machine with respect to the gauges of the feed table, in which the sheets caught by rotating grippers are pressed out of the path of the grippers by special means to accelerate the rear end of the sheets, characterized in that the press-out member is a sheet carrying drum or a portion of a cylindrical surface rotating about a center eccentrically located relative to the center of the path of the grippers, and that the grippers and the sheet carrying drum are connected by suitable means, as a crank guide, to insure uniform rotary motion, said guide being in the head members of the press out drum.

2. A device according to claim 1, in which the degree of eccentricity between the center of the path of the grippers and that of the sheet carrying drum is adjustable.

3. A device according to claim 1, in which the sheet carrying drum is eccentrically arranged on the shaft of the gripper carriers and said shaft is connected with said drum by a coupling permitting radial motion and enforcing rotary motion.

4. A device according to claim 1, in which the press-out member connecting with the preliminary gripper connects with a second sheet press-out member.

5. A device according to claim 1, in which the press-out member connecting with the preliminary gripper connects with a second sheet press-out member which is of the same or similar type as the first press-out member.

6. A device according to claim 1, in which the press-out member connecting with the preliminary gripper connects with a second sheet press-out member of the same or similar type as the first press-out member and the said two members, with respect to eccentricity, are preferably directed parallel but oppositely so.

7. A device according to claim 1, in which the running-on surface of the press-out member having the form of the superficies of a cylinder is tangent to the path of the front edge of the sheet determined by the conveying grippers.

8. A device according to claim 1, in which the press-out member connecting with the preliminary gripper connects with a second sheet press-out member of the same or similar type as the first press-out member and sheet holding means, as brushes, smoothing members, blast or suction air means, are associated with the press-out members.

9. A device according to claim 1, in which a plurality of press-out members are arranged one after the other, the number and dimensions thereof depending upon the length of the sheets.

10. A device according to claim 1, in which a plurality of press-out members are arranged one after the other, the number and dimensions thereof depending upon the length of the sheets, and the eccentricities of said members are variable relative to one another.
